(57) **CLAIM**

The ornamental design for a cymbal clutch, as shown and described.

DESCRIPTION

FIG. 1 is a perspective view of a cymbal clutch;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is an environmental perspective view thereof.

The broken lines showing the cymbals and post illustrate the environment of the claimed design and form no part thereof. The remaining broken lines showing the cymbal clutch are included for the purpose of illustrating portions of the article and form no part of the claimed design. The shade lines rendered in the drawings are meant to show contour and form no part of the claimed design.
